UNITED STATES PATENT OFFICE

132,528

DESIGN FOR A BANNER OR SIMILAR ARTICLE

Robert C. Stephens, Covington, Ky.

Application January 28, 1942, Serial No. 105,488

Term of patent 3½ years

To all whom it may concern:

Be it known that I, Robert C. Stephens, a citizen of the United States, residing at Covington, in the county of Kenton and State of Kentucky, have invented a new, original, and ornamental Design for a Banner or Similar Article, of which the following is a specification, reference being had to the accompanying drawing, forming part thereof.

The figure is a plan view of a banner or similar article, showing my new design.

I claim:

The ornamental design for a banner or similar article, as shown.

ROBERT C. STEPHENS.
